WINE BUCKET STAND

David P. Rhame, 871 Mandalay Beach Road,
Oxnard Shores, Calif.

Filed Mar. 24, 1965, Ser. No. 84,423

Term of patent 14 years

(Cl. D33—3)

FIG.1.

FIG.2.

FIG.3.

FIG.4.

I claim:

The ornamental design for a wine bucket stand substantially as shown.
